UNITED STATES PATENT OFFICE.

CLAUD D. CURRY, OF MASSILLON, OHIO, AND FREDERICK W. EWALD, OF NEW YORK, N. Y., ASSIGNEES, BY DIRECT AND MESNE ASSIGNMENTS, TO AMERICAN ASSEMBLING MACHINE COMPANY, A CORPORATION OF DELAWARE.

SIGNATURE-OPENING DEVICE.

1,202,270.

Specification of Letters Patent. Patented Oct. 24, 1916.

Application filed July 24, 1914. Serial No. 852,780.

To all whom it may concern:

Be it known that we, CLAUD D. CURRY and FREDERICK W. EWALD, both citizens of the United States, and residents, respectively, of Massillon, county of Stark, and State of Ohio, and of the borough of Brooklyn, New York city, county of Kings, and State of New York, have invented certain new and useful Improvements in Signature-Opening Devices, of which the following is a specification.

This invention relates to improvements in opening devices for folded paper sections and is particularly adapted for use in connection with paper associating machines of the type shown in the patent to Claud D. Curry, #1,117,000, Nov. 10, 1914. In the device shown in the patent, opening or spreading devices were employed which consisted principally of two parallel endless chains carrying spreader members arranged to travel between the plies of a partially opened paper section. This structure was found in practice to be more or less cumbersome, and an object of this invention is to provide paper section opening or spreading means which will be more simple in construction and capable of more rapid operation.

A feature of the invention is the provision of opening mechanism including needle boxes for initially opening the paper section, a separating finger for further opening the section, and a pivoted spreading device arranged to be swung into the partially opened section to complete the opening thereof for the reception of an insert.

In the accompanying drawings, Figure 1 is a plan view of the preferred embodiment 40 of the invention; Fig. 2 is a side elevation of the device shown in Fig. 1 looking in the direction of the arrow 2 in Fig. 1; Fig. 3 is a transverse vertical sectional view of the opening mechanism taken substantially on the line 3-3 of Fig. 2; Fig. 4 is a plan view showing one of the needle boxes carried by the opening members; Fig. 5 is a front elevation of a needle box looking in the direction of the arrow 5 of Fig. 4.

In Figs. 1 and 2 the numerals 1 and 2 represent the inside lines of a framework in which the mechanism about to be described is mounted. Mounted on the framework 2

is a fixed bracket 3 to which is pivoted at 4 a paper section guiding and spreading device 5. The device 5 is made up of two parallel members between which the paper sections pass in their progress from a hopper or feeding device overhead into the paper section opening or separating mechanism. 60 When a paper section A passes downwardly through the guiding device 5 it comes to rest preliminary to the operation of the opening mechanism, upon the paper supports 6, carried by shafts 7 and 8 journaled in the frame 1 and 2. The paper supports 6 are in the form of depending blades and are arranged in pairs, the lower edges of which curve inwardly to meet each other as is shown at 9 in Fig. 3 of the drawings. 70

In dropping onto the supporting members 6 the paper section will enter between two devices 10 and 11 which may be termed needle boxes and whose function it is to perform the initial opening of the folded paper section. The needle boxes are so located as to engage the paper section near one end and the free edge, while the remaining end is caught and held between two rotating cone-shaped tension rollers 12 and 13. 80

The needle boxes are carried by the opening members or frames 14 and 15 which are mounted on hubs 16 and 17 adapted to rock or oscillate about shafts 18 and 19. On the hubs 16 and 17 are provided toothed segments 20 which intermesh and by means of which the members 14 and 15 can be operated in unison. An arm 21, integral with hub 16, is connected through the links 22 with a lateral extension 23 of the vertically reciprocating slide 24. A cam roll 25, carried by the slide, is adapted to be engaged by the cam 26 on the drive shaft 27 to give motion to the slide and thence to the opening members and needle boxes carried thereby. A bracket 28 mounted on the frame piece 1 is provided with a slideway in which the slide 24 reciprocates. 90

Referring now to Figs. 4 and 5 in which the specific construction of the needle blocks is illustrated, there is shown at 29 a needle box supporting member which is bolted to the corresponding opening member. Extending laterally from the supporting member are two arms 30 and 31 provided with guideways 32 and 33. Arranged

to reciprocate between the arms 30 and 31 and to engage the guideways 32 therein, is the needle box, or carrier, 34 on which the needles 35 are mounted. The needle carrier 5 is reciprocated between the arms 30 through the action of a cam 36 carried on shaft 19 which operates a lever 37 which in turn transmits motion to the carrier 34 through the eye bolt 38 which is secured to the 10 needle-carrier by the pin 39. The other needle carrier is driven from a corresponding cam on the shaft 18.

In order to regulate the effective length of the needles necessary for piercing the 15 plies of the paper section, there is provided a face plate 40 adapted to be adjusted with relation to the supporting member 29 on which it is mounted. The face plate 40 is provided with a boss 41 which is arranged 20 to engage the threaded portion of a bolt 42. The bolt 42 has an unthreaded portion which passes through the supporting member 29 so that the bolt can be turned freely within the support. A nut 43 at one end 25 prevents longitudinal movement of the bolt. A micrometer head 44 fixed to the bolt has a scale adapted to be read in relation to a mark 45 on the supporting member 29.

When the micrometer head is turned the 30 bolt 42 is rotated and the face plate is moved laterally with respect to the needle carrier support. This, as will be obvious, will affect the length of the portions of the needles which project through the face 35 plate and a means is thus provided for adjusting the length of the needle projections to accord with the thickness of the paper sections which are to be operated upon. The face plate slides on the needle block 40 support and is secured by screws 46 which pass through slots 47 in the guide plate.

The cone-shaped tension rollers 12 and 13, which have been already referred to, serve 45 to pull the paper section taut and facilitate the opening of the section. The tension roller 13 is journaled in a bearing formed in the end of a fixed bracket 48 carried by the framework 2. A bevel gear 49 meshing with a bevel gear 50 mounted on the shaft 50 19 is adapted to give rotation to the tension roller 13 through the shaft 13'. The fixed bracket 48 also forms a support at 51 for one end of one of two shafts 52 which will be hereinafter referred to. A second fixed bracket 48 corresponding to the fixed bracket 48 already referred to provides a bearing 55 for the other of the two shafts 52.

The tension roller 12 is mounted on a 60 bracket 53 pivotally mounted on the shaft 18. The swinging tension roll 12 is held in yielding engagement with the stationary roller 13 by means of a spring 54 mounted on a rod 55 pivoted to the bracket 48 at 56. An adjustable yielding stop 57 mounted on 65 the fixed bracket 48 limits the inward move-

ment of the swinging bracket 53. The tension roller 12 is driven from the shaft 18 through shaft 12' and a bevel gear connection corresponding to the driving connection for the roller 13.

Carried by the bracket 56' on the frame 1 is a rock shaft 57' on which is mounted the separating finger, or blade, 58 adapted to be swung inwardly between the plies of the paper section just after they have been 70 initially separated by the operation of the needle blocks. The action of the separating finger brings about a further separation of the plies preparatory to the final spreading operation of the member 5 which will hereinafter be referred to. Motion is transmitted to the rock shaft 57' at the proper moment in the sequence of operations, by means of the arm 59 carried by the rock shaft 57', the link 60, and rock arm 61 75 pivoted at 62 on bracket 63 which is attached to the frame 1. A rod 64 pivoted to rock arm 61 is adapted to be reciprocated by cams 64' on the drive shaft 27 already referred to.

The construction of the member 5 by which the paper section opening function is obtained is as follows: At the end remote from the pivot point 4 the device 5 has a pivotal connection with a link 65 which is in turn connected to an arm 66 mounted on a rock shaft 67, journaled in the bracket 56 on the framework 1. Through another arm 68, mounted on the rock shaft, a link 69 and a rod 70 adapted to be reciprocated 80 by the operation of a cam 71 on drive shaft 27, motion can be transmitted to rock shaft 67 and thence to the spreading device 5 thereby causing the spreader to rock downwardly about the pivot 4 to spread apart 85 the already partially separated plies of a paper section. Carried by the spreader 5 are the fingers 72 which assist in the spreading or separating operation, and are arranged in progressively increasing lengths 90 from the pivot point in order to spread the paper section evenly and prevent buckling.

In the operation of the device so far described a folded paper section passes from the hopper, or feeder, down through the 115 guiding device 5 and drops onto the paper supports 6 which at this point in the operation are closed as shown in Fig. 3, the opening members, or frames, 14 and 15 being at this moment in their separated position and 120 the cut-away portion of the tension rollers 12 and 13 being innermost, or adjacent each other to permit the paper to pass into position on the paper supports. When this has taken place the opening members are swung 125 to their closed position and the folded paper section is caught by the yieldable stops, or holding devices, 73 mounted in the needle blocks themselves, and the stops, 74 mounted in the arms 75 which are attached to the 130

hubs 16 and 17. The paper stops hold the paper section in upright position and prevent buckling or collapsing of the section. When the needle blocks have been moved to 5 a position in engagement with the paper section the needle carriers are reciprocated through the action of the cams 36 to cause the needles to pierce the respective plies of the paper section while the tension rollers 10 at the other end of the paper section at the same time seize the section and pull it taut. The next step in the operation of the device is the moving apart of the opening members whereupon the two plies of the 15 folded paper section, which are held by the needles, are initially separated. This operation is immediately followed by the swinging forward of the separating blade 58 to further separate the plies and prepare them 20 for the operation of the spreader members 5 which now swing downwardly to move the plies to their extreme limit of separation. At this point in the operation a paper section, which is to be inserted within the 25 opened section, passes down through the spreader member 5 into place within the opened paper section. The cams 36 are so timed as to withdraw the needles and release the paper section as soon as the insert has 30 been deposited. At the same time the paper supports 6 are opened to release the paper section by the rocking of the shafts 7 and 8 on which the paper supporting members are mounted. An arm 76 mounted on the 35 shaft 8 is adapted to be oscillated to rock the shaft 8 by the reciprocating movement of the rod 77 which may be driven in any suitable manner from the drive shaft 27 as by means of the arm 93 operated by cam 94 40 on said shaft. Intermeshing gear segments 78 carried by the shafts 7 and 8 serve to bring about the operation of the shafts 7 and 8 and consequently the supporting members 6 in unison. The rocking of the shafts 7 45 and 8 opens the paper supports 6 and allows the "stuffed" paper section to pass downwardly therethrough and through guiding members to the final ejecting rolls 79 mounted on the shaft 95.

50 To assist in the downward movement of the stuffed paper section two sets of discharging or ejecting rollers 80 are provided which are carried by the shafts 52 already mentioned. An arm 81 mounted on one of the shafts 52 is adapted to be oscillated by 55 the reciprocating movement of the rod 82 which, like the rod 77, may be driven in any suitable manner from the drive shaft 27 as by means of the arm 91 operated by the cam 92 on said shaft. Intermeshing gear segments 83 carried by the shafts 52 serve to operate the shafts in unison. Carried by the shafts 52 are arms 84 each of which carries a pair of the ejecting rolls 80. One set 60 of the ejecting rolls is caused to operate through the gears 85, 86, and 87, and thence through a flexible shaft 88 from the driving gear 89 meshing with the gear 90 on shaft 27. When the shafts 52 are rocked to bring the rolls 80 into engagement with the intervening paper section the rotation of the rolls, which are driven from the shaft 88, will eject the paper section, the movement of the paper rotating the remaining and idle rolls by frictional engagement therewith. 70

The moving parts are so related and timed that the passage of a paper section through the apparatus is immediately followed by the restoration of the mechanism to a position in readiness to receive and stuff another section as will be evident. 80

What is claimed, is:

1. A signature opening device including: means for partially opening a folded paper section, and swinging means having a movement in a plane substantially parallel to the folds of the section for further opening the section. 85
2. A signature opening device including: means for supporting a folded paper section in an upright position, means for partially separating the folds of the section, means for further separating said folds, and a vertically moving member coöoperating with 90 said separating means for still further separating said folds of the section. 95
3. A signature opening device including: means for partially opening a folded paper section, and swinging means moving in a plane substantially parallel to the folds of the section and toward and from the folded edge thereof for further opening the section. 100
4. A signature opening device including: means for partially separating the plies of a folded signature, oscillating means moving in a plane substantially parallel to the folds of the signature for further separating said plies, and oscillating means coöoperating with the separating means for still further 105 separating said plies. 110
5. A signature opening device including: means for supporting a folded signature in an upright position with the folded edge lowermost, means for partially opening the 115 signature, and means comprising a separator blade for further separating the folds of the signature and spreader bars for still further separating said folds. 120
6. A signature opening device including: means for supporting a paper section in an upright position, means for partially opening the section while so supported, means moving upwardly and between the partially separated folds of the section for further 125 separating the same, and means moving downwardly to coöperate with the upwardly moving means for completing the opening of the section. 125
7. A signature opening device including: 130

means for initially and partially opening a folded paper section at a corner thereof, swinging means moving between the partially separated folds of said section to separate further the folds thereof, and a second swinging means to still further separate said folds of the section.

8. A signature opening device including: means to support a folded signature, means 10 to guide the signature to the support, means to initially and partially open the signature while being supported, means to further separate the folds of the signature, and means to operate said guiding means to 15 more completely open the signature.

9. A signature opening device comprising: means for supporting a folded signature in an upright position with its fold lowermost, guides in spaced relation to each 20 other above said supporting means, means for partly opening said folded signature, and means for causing said guides to descend to complete the opening of the folded signature.

25 10. A signature opening device including: means for opening a folded paper section at one corner means to enter between the separated folds at said corner for further separating the folds of the section, and means 30 arranged to move on opposite sides of said separating means for still further spreading said separated folds of the section.

11. A signature opening device including: means for supporting a folded paper section 35 in an upright position, means partially opening said section while so supported, a separating blade adapted to swing between the partially separated folds of the section, means to operate the blade, a pair of spaced 40 and parallel bars to normally lie above the opened edge of the section, and means for swinging said bars for further separating the folds of the section.

12. In a signature opening device, means 45 to partially open a folded paper section at a corner thereof, and swinging means movable substantially parallel with the folds of the section and toward and from the folded edge thereof to progressively spread the 50 folds of the section from the point of initial separation and thereby increase the opening of the section.

13. A signature opening device including: a pair of opening devices, means to support 55 a folded signature between said opening devices in an upright position with its folded edge lowermost, means to operate said opening means to partially separate the folds of the signature at a corner thereof, means for 60 further separating the folds of the signature, and means movable vertically to progressively spread the separated folds of the signature from the point of initial separation and thereby still further open the signature.

65 14. In a signature opening device, means

for supporting a folded signature in an upright position with its fold lowermost, guides in spaced relation to each other above said supporting means, means for partly opening said folded signature at one corner thereof, 70 means for causing said guides to descend to progressively spread the folds of the signature from the corner thereof initially opened and thereby increase the opening of the signature.

75 15. In a signature opening device, two relatively movable opener frames, means for operating said frames, means for supporting a folded paper section between the frames, means carried by the frames and coöperating 80 with each other for partially opening the section, a pivoted separating blade arranged to move between said frames to further separate the folds of said partially opened paper section, means for operating the blade, and means for still further separating the folds 85 of said section.

16. In a signature opening device, two relatively movable opener frames, means for operating said frames, means for supporting a folded paper section between the frames, means carried by the frames above said supporting means and coöperating to partially 90 open the section, a pivoted separating blade arranged to move between said frames and the folds of said partially opened paper section, means for operating the blade, and pivoted spreading bars arranged in spaced 95 relation to move on opposite sides of the separating blade and between the separated folds of the section for further opening the same.

17. A signature opening device including: two relatively movable opener frames, means to move the frames to and away from each other, means for supporting a folded paper section between the frames, means carried on the frames for partially opening the section while being supported, a support, a blade pivoted to the support and arranged to move between the folds of the partially 105 opened paper section, a second support, spaced and parallel bars pivoted to the second support to swing between the folds for increasing the degree of opening of the section, and means to operate said blade and bars.

110 18. In a signature opening device, two relatively movable opener frames, means to support a folded paper section between the frames, means on the frames for partially opening the section, a support, a blade pivoted to the support and arranged to move inwardly and upwardly between the folds of the partially opened paper section for separating the folds thereof, means to operate the blade, a second support, spaced and parallel bars pivoted to said second support to swing between the folds of the section, and means 115 for operating the bars for moving the same 120

125 130

downwardly in coöperation with said blade so that the section will be more completely opened.

19. A signature opening device including: 5 movable opener frames, pairs of movable guides adapted to form a support for a folded paper section between the opener frames, intermeshing sectors for swinging the guides in unison and in opposite directions, means carried by the frames for partially opening the section, means for more completely opening the section, and means to impart motion to one of said sectors whereby said guides will open so as to deliver the 15 section.

20. In a signature opening device, means to support a folded signature, pivoted frames arranged on opposite sides of the supporting means, ejecting rollers for ejecting the signature from the support, and means for moving said frames toward and away from each other to engage and open the paper section.

21. In a signature opening device, a movable support for a folded signature, means for moving the support to release the signature, frames arranged to move on opposite sides of the support, ejecting rollers journaled in the frames to engage said signature for ejecting the same, means for imparting motion to the rollers, and means for swinging said frames toward and away from each other to bring the rollers into engagement with the signature so as to eject the 35 signature when the support has released the same.

22. In a signature opening device, relatively movable opener frames, relatively movable means for supporting a folded 40 signature between said opener frames, means on said frames for partially opening the signature, means for more completely opening the signature, means for moving the support to release the signature, a second 45 pair of frames arranged to swing on opposite sides of the supporting means, ejecting rollers journaled in the second frames, means to rotate the rollers, and means for swinging said second frames to move the 50 rollers into and out of engagement with the signature for ejecting the same when released by said supporting means.

23. A signature opening device comprising two relatively movable guides adapted 55 to have their lower ends brought together to form a support for a folded signature, means for opening the signature, means for imparting motion to one of the guides, means for moving the other guide from said 60 first guide in unison and in an opposite direction so that the guides will open to release the stuffed signature, relatively mov-

able frames arranged on opposite sides of the supporting means, ejecting rollers journaled in said frames, means for rotating 65 the rollers, means for imparting motion to one of said frames, and means for moving the other of said frames from said first frame in unison and in an opposite direction for moving the ejecting rollers together 70 so as to eject the signature when said support is opened.

24. A signature opening device including: a pair of spaced apart pivoted arms, inwardly extending overhanging portions 75 formed on the free ends of said arms, opening means mounted on the said overhanging portions of the arm, means disposed between said arms for supporting a folded signature therebetween, and means disposed 80 between said arms for ejecting the signature from said supporting means.

25. A signature opening device including: a pair of spaced apart pivoted arms adapted to swing toward and from each 85 other, inwardly extending overhanging portions formed on the upper ends of the arms, spaced and relatively movable means disposed between said arms for supporting folded signatures therebetween in an upright position, means mounted on said overhanging portions of the arms for partially opening the signatures while being supported, means movable between said arms for more completely opening the signatures, 90 and spaced and relatively movable means disposed between said arms for ejecting the signatures from between said arms.

26. In a signature opening device, swinging members adapted to be brought together 100 to form a support for a folded paper section, swinging means to partly open the section while supported, swinging means for more completely opening the section, means to separate said supporting members, and 105 swinging means carrying ejecting rollers to be brought together for ejecting the section when said supporting members are separated.
